CLAIM

The ornamental design for a surface-mountable heat sink, as shown and described.

DESCRIPTION

FIG. 1 is a top view of the first embodiment of the design for a surface-mountable heat sink;

FIG. 2 is a front elevational view thereof, the opposite rear view being the same;

FIG. 3 is a side elevational view thereof, the opposite side view being the same;

FIG. 4 is a bottom view thereof; and

FIG. 5 is a front, top perspective view thereof.

FIG. 6 is a top view of the second embodiment of the design for a surface-mountable heat sink;

FIG. 7 is a front elevational view of the second embodiment, the opposite rear view being the same;

FIG. 8 is a side elevational view of the second embodiment, the opposite side view being the same;

FIG. 9 is a bottom view of the second embodiment; and,

FIG. 10 is a front, top perspective view of the second embodiment.
